UNITED STATES PATENT OFFICE

WILLIAM W. HENDERSON, OF SAN FRANCISCO, AND RUDOLF A. ISENBERG, OF LOS ALTOS, CALIFORNIA

OUTDOOR-SPORTS FIELD

Application filed August 2, 1929. Serial No. 383,126.

Our invention relates to improvements in playing fields for outdoor sports wherein a cement basin having means for draining water therefrom is provided with a plurality of removable fibrous mats fitted therein to form a resilient playing field for outdoor games.

The primary object of our invention is to provide an improved field for outdoor sports and games.

Another object is to provide an improved field having a playing surface formed from resilient fibrous mats removably fitted within a cement basin whereby the mats may be removed in case of rain to permit effective draining of the basin and restored in a dry condition when play is to be started.

A further object is to provide an improved field wherein a cement basin is provided with draining means adapted to facilitate the draining of rain or other accumulations of water therefrom.

Another object is to provide an improved field having a draining basin and provided with removable fibrous mats which may be removed in case of rain before a game is to be played, and through which rain may be effectively drained during the course of a game without materially interfering with the conduct of the game.

A further object is to provide an improved field of the character described wherein removable mats are effectually pressed and wedged together to give a smooth, even playing surface.

Another object is to provide an improved field wherein fibrous mats are detachably secured to the bottom of a draining basin to facilitate removal and replacement as desired.

A still further object is to provide an improved field of the character described which will obviate postponement of sports and athletic contests because of rain or rain soaked fields, and which will reduce discomfort to players engaging in sports during or immediately after a rain.

We accomplish these and other objects by means of the improved device disclosed in the drawings, forming a part of the present application wherein like characters of refer-

ence are used to designate similar parts throughout the specification and drawings, and in which—

Fig. 1 is a plan view of our improved sports field, part of the mats being removed;

Fig. 2 is a broken transverse sectional view taken through the center of the field and drawn upon a larger scale;

Fig. 3 is an end elevation of two mats showing the diverging sides thereof; and

Fig. 4 is a sectional view showing the manner in which the mats are secured within the basin, the securing means being shown upon an exaggerated scale.

Referring to the drawings, the numeral 1 is used to designate in general a foundation basin formed from cement or other suitable material impervious to water. The bottom of the basin is made flat and the sides and ends of the basin extend upwardly from the bottom as at 2 to substantially the plane of the surface of the ground surrounding the basin.

A suitable drain 3 opens into the basin, preferably at the center of the bottom, said drain being extended to carry water from the basin to any suitable point of discharge in any convenient manner, not shown in the drawings. Main drain channels 4 extend longitudinally from the ends of the basin 1 to the central drain 3, the bottoms of said drain being inclined downwardly from the ends of the basin to the drain whereby water will flow along said channels to the drain. A plurality of transverse channels 6 are formed in parallel relation from the sides of the

basin to the main channels 4, the bottoms of said channels 6 being inclined downwardly from the sides of the basin to the level of the bottom of the main channel at the point of intersection whereby water will flow along said transverse channels to the main channels.

A plurality of feeder channels 7 are formed in the bottom of the basin to intersect with the transverse channels 6, preferably at right angles. The bottoms of the

feeder channels 7 incline from the surface of the bottom of the basin to the bottoms of the channels 6 at the points of intersection to flow water from the bottom surface to said transverse channels and thence to the drain.

A plurality of mats 8 are removably fitted into the basin to surface bottom and the sides and ends of said basin. The mats 8 are formed from fibrous material such as jute, hemp, or other suitable material, preferably in rectangular form with the sides and ends diverging upwardly from the bottom to the top surfaces of each mat, as shown in Fig. 3. The mats 8 along the sides and ends of the field are provided with flange like extensions 9 shaped to extend over the adjacent side and end walls 2 of the basin. The mats are made preferably of a thickness slightly less than the depth of the basin, and the extensions 9 are shaped to extend upwardly and across the end and side walls to provide a substantial thickness of the matting material over the cement.

The mats 8 are preferably secured to the bottom of the basin 1 by means of suitable securing members 11 seating within the counter-sunk apertures 12 formed in the mat and spaced to correspond to recessed members 14 inset in the bottom of the basin, as indicated in exaggerated scale in Fig. 4 of the drawings. In the preferred construction illustrated, the securing members 11 consist of screws threaded to engage the members 14, washers 16 being provided to form seats for the heads of the screws 11.

Fillers 17 formed from material similar to the mats 8 are fitted between the adjacent edges of desired rows of mats to define boundaries or other markers, as desired, for laying out any particular playing field. The fillers are preferably colored in any suitable manner and are made of a suitable thickness to provide distinct marking lines. In Fig. 1 the fillers are illustrated as arranged to define the boundaries and transverse yard lines of a foot-ball field. However, the fillers may be arranged to define the playing field for other games or sports as desired.

In operation, the mats 8 are fitted into the basin 1 as indicated in Fig. 1. The flaring relation of the sides and ends facilitates the placing of the mats in the desired arrangement so that when the securing members 14 are applied to draw the mats down tightly against the bottom of the basin, the flaring sides and ends will be compressed together so that the upper edges of adjacent mats will fit and be wedged tightly together to give a smooth uninterrupted surface. The fillers 17 are effectually held by the wedging action of the sides and ends of the mats 8 when secured in the basin. The mats are made several inches in thickness so that a firm and durable surface is provided, and, at the same time, providing a resiliency adapted to prevent injury to players who may fall or be thrown upon the field. The fibrous material further provides a surface which will afford a good footing for players and thereby increase the speed and precision with which sports may be played. The mats are sup-

ported in a smooth even plane by the flat bottom of the basin.

In case of rain, the mats 8 are removed from the basin and stored in a suitable shelter. Rain, or water accumulating in any manner upon the field will now flow freely through the drainage channels 7, 6, and 4 to the drain 3. Just before the time when the sport is to be started, the mats are replaced, thereby providing a dry field upon which the sport may be played. In this manner, games may be played according to schedule which would otherwise have to be postponed because of the wet condition of the ordinary playing field.

In event it should rain during the course of a game, the rain will readily drain through the fibrous mats and flow through the drainage channels to the drain outlet, thus preventing the accumulation of water in sufficient quantity to materially handicap the players or cause severe discomfort. Our invention is of particular value as a foot-ball field because of this reason, as heretofore such games have been played regardless of the condition of the field with the result that players have been subjected to extreme discomfort, and the game has been made slow and uninteresting to the spectators.

Our invention is, of course, subject to modification to meet the requirements of specific locations and of various games, and we desire to avail ourselves of all such modifications as may fall within the scope of the appended claims.

Having thus described our invention what we claim as new and desire to secure by Letters Patent is:—

1. An outdoor sports field comprising a cement basin having a flat bottom and provided with a central drain opening at a point below the plane of the bottom; main drain channels formed in the bottom of the basin and having the bottom thereof inclining longitudinally from the ends of the basin to the central drain; a plurality of transverse drain channels intersecting with the longitudinal drain channels and having their bottoms inclined from the sides of the basin to said longitudinal channels; a plurality of feeder channels intersecting each transverse channel and having their bottoms inclined from the surface of the basin to the bottoms of said transverse channels; and a plurality of resilient fibrous mats removably fitted into and surfacing the basin, said mats being supported upon the bottom of the basin clear of the channels to form a smooth level playing field.

2. An outdoor sports field comprising a cement basin provided with draining means formed in the bottom thereof to drain water therefrom; and a plurality of resilient fibrous mats fitted into the basin and surfacing the same to form a playing field, the mats adjacent the sides of the basin being extended

over said sides to cover said sides and protect players from injury thereon.

3. An outdoor sports field comprising a cement basin provided with draining means formed in the bottom thereof to drain water therefrom; and a plurality of resilient fibrous mats removably fitted into the basin and surfacing the same, each mat having its sides and ends diverging upwardly whereby the mats may be pressed and wedged into tight contact when fitted into the basin to form a playing field.

4. An outdoor sports field comprising a cement basin provided with draining means formed in the bottom thereof to drain water therefrom; a plurality of resilient fibrous mats removably fitted into the basin and surfacing the same, each mat having its sides and ends diverging upwardly whereby the mats may be pressed and wedged into tight contact when fitted into the basin to form a playing field; and extensions formed upon the outer edges of mats adjacent the sides and ends of the basin to overhang said sides and ends.

5. An outdoor sports field comprising a cement basin provided with draining means formed in the bottom thereof to drain water therefrom; a plurality of resilient fibrous mats removably fitted into the basin and surfacing the same, each mat having its sides and ends diverging upwardly whereby the mats may be pressed and wedged into tight contact when fitted into the basin to form a playing field; extensions formed upon the outer edges of mats adjacent the sides and ends of the basin to overhang said sides and ends; and resilient fibrous fillers inserted between adjacent rows of mats to form boundaries and suitable markers upon the field.

6. An outdoor sports field comprising a cement basin provided with draining means formed in the bottom thereof to drain water therefrom; and a plurality of resilient fibrous mats fitted into the basin and surfacing the same to form a playing field; and resilient fibrous fillers inserted between adjacent rows of mats and having their upper edges exposed and colored to define suitable boundaries and markers upon the field.

In witness whereof, we hereunto set our signatures.

WILLIAM W. HENDERSON.
RUDOLF A. ISENBERG.
